Filed Oct. 7, 1964, Ser. No. 82,071

Term of patent 14 years

(Cl. D48—20)

FIG. 1

FIG. 3

FIG. 1 is a side elevational view of a nursery lamp or similar article showing my new design, the side opposite being the same as that shown.

FIG. 2 is a top plan view thereof; and

FIG. 3 is a perspective view thereof.

The bottom of the lamp base has six feet, the two feet at the rear being located directly behind the two innermost feet shown in FIG. 1.

I claim:

The ornamental design for a nursery lamp or similar article, substantially as shown and described.
